[57] CLAIM

The ornamental design for a combined light dimmer knob and escutcheon therefor, as shown and described.

DESCRIPTION

FIG. 1 is a perspective view of a combined light dimmer knob and escutcheon therefor showing our new design;

FIG. 2 is a front elevational view thereof, the rear being flat and unornamented;

FIG. 3 is a bottom plan view thereof;

FIG. 4 is a sectional view taken in the direction of the arrows on line 4—4 of FIG. 3.

FIG. 1.FIG. 2.FIG. 4.FIG. 3.
